UNITED STATES PATENT OFFICE.

HORACE E. SMYTHE, OF PITTSBURGH, PENNSYLVANIA.

FURNACE.

Application filed February 28, 1921. Serial No. 448,685.

To all whom it may concern:

Be it known that I, HORACE E. SMYTHE, a citizen of the United States, residing at Pittsburgh, in the county of Allegheny and 5 State of Pennsylvania, have invented new and useful Improvements in Furnaces, of which the following is a specification.

My invention relates to furnaces and more particularly to metallurgical furnaces where 10 in oil is used as a fuel.

The object of this invention is to provide for furnaces of the open hearth or other type readily operated means whereby oil burners may be easily withdrawn from, and restored 15 to, their normal positions. Another object is to provide means whereby such burners may be so withdrawn and restored by the furnace attendant from a single station, preferably at the back of the furnace where 20 the oil and steam or air regulating stand is located. Other objects pertain to the details and their combinations.

Referring to the accompanying drawings, Fig. 1 is a vertical section through a portion 25 of one end of an open hearth furnace, showing parts of my invention in side elevation; Fig. 2, a vertical cross-section of Fig. 1 on the line II--II; Fig. 3, a horizontal section of Fig. 1 on the line III--III; Fig. 4, a rear 30 view of the furnace, showing the means by which the burners are operated from the back of the furnace; Fig. 5, an enlarged view showing my burner and its supporting means in side elevation, some adjacent parts 35 being in section; Fig. 6, a vertical longitudinal section through one of the burners and its supporting means, a part being in section; and Fig. 7, a sectional detail of a fragment of the burner carriage.

40 On the drawings, 1 designates the hearth of an open-hearth furnace and 2 the combustion chamber at one end of the furnace, it being understood that there is a similar combustion chamber at the end of the furnace 45 opposite that shown. As is usual the combustion chamber is somewhat above the bottom of the melting chamber 3.

4 is an oil-burner comprising the burner head 5 with the axial passage 6 extending 50 from the end thereof. The ends of this passage are threaded to receive the burner pipe 7 and the oil inlet fitting 8. At the oil-receiving end of the burner-head 5, the passage 6 is contracted and threaded toward the 55 other end to receive the oil-carrying pipe 9 somewhat smaller than the said passage and

projecting a short distance from the burner-head into the burner-pipe. 10 is a fitting screwed into an opening in the side of the burner-head for the conveyance of steam or 60 air or both into the burner-head. The free end of the burner-pipe 7 is held by the carriage 15 so that normally it projects the required distance into the combustion chamber through the opening 11 in the end wall 65 12 of the furnace. Preferably the pipe 7 is arranged in the flaring depression 13 arranged longitudinally of the chamber 2 and centrally between the sides thereof. This depression may be opened upwardly as 70 shown. At each side of the combustion chamber is a vertical flue or passage 14 leading to the usual or preferred type of regenerator. This feature is common and forms no part of the invention defined by the ap- 75 pended claims.

The bracket 16 provided with the upwardly and outwardly inclined sockets 17 is secured to the furnace or other support above the opening 11. A pair of inclined 80 rods 18 and 19 have their lower ends secured in the said sockets by the set screws 20. The outer ends of the rods are secured by the set screws 21 in openings in the spacer 22. The upper end of the spacer is connected by the 85 adjustable braces 23 to the furnace. The lower end of the spacer 22 supports the sheave 24 with its pivot 25 at right angles to the plane through both rods 18 and 19.

The carriage 15 has the side plates 26 at 90 opposite sides of the said rods and supported on the axle 27 of the wheel 28 lying between the rods and grooved to receive both of them, whereby the wheel is supported by the rod or track 18 and prevented from lateral and wabbling movements. The axle 27 supports the pendent bars 29, one at each side of the wheel. They are spaced apart at their lower end by the block 30 bolted thereto and carrying the upwardly and outwardly 100 inclined stud 31. This stud is secured by the set-screw 32 in an opening 33 in the tie-block 34 having an opening 35 in which the burner head 5 is secured by the set-screw 36. The plates 26 carry the cross-piece 37 105 in which the screw 38 is swiveled, while the threaded end of the screw works in the nut 39 carried by the bars 29. 40 is a wing or handle for turning the screw. By turning the handle 40 the angular relation of the 110 burner pipe 7 can be adjusted in a vertical direction. The carriage 15 is provided with

the two grooved wheels 41 and 42, one running on the upper side of the rod 19 and the other on the lower side thereof to prevent the carriage from rocking on the axle 5 27 and from lateral movements.

Each end of the furnace has the same construction as that described and shown, and each end thereof has a burner mounted and operated like that just described. On Fig. 10 4 I have shown each side of the furnace with a pair of rods 18 and 19, a spacer 22, and a sheave 24 at each end thereof. Each carriage 15 has attached thereto an operating cable 43, which passes over the adjacent 15 sheave 24 and thence downwardly under the sheaves 44; thence horizontally over the sheave 45 and under the sheave 46 toward the rear of the furnace; and thence upwardly and over the sheave 47 and under the sheave 20 48 toward the center line of the rear of the furnace. The sheaves 44 to 48 are beneath the furnace structure. From the sheave 48 the cable 43 passes upwardly and over the sheave 49 which is above the floor at one 25 side of the regulating stand 50 where the furnace attendant is stationed. From the sheave 49 the cable extends downwardly through the two stop-guides 51 and 52. A handle or stop 53 is attached to each cable 30 between the stop-guides. The handle 53 engages the stop-guide 51 when the carriage 15 is at its lower or inner position and against the stop-guide 52, when the carriage is at its outer position which is next to the spacer 35 22. Fig. 4 shows diagrammatically the furnace and the course of the cables 43 with some of the parts associated therewith. A counterweight 61 is connected to each cable below the stop-guide 52 to counterbalance 40 the carriage 15 and its load.

54 is an oil-supply pipe at the rear of the furnace and has a vertical pipe 55 between the cables at the operator's stand 50. The top of the pipe 55 which is within easy reach 45 of the operator is provided with the horizontal pipe 56 extending in opposite directions from the pipe 55. At each end of the pipe 56 is connected the downwardly extending vertical pipe 57, the pipes 57 being respectively connected to the horizontal pipes 58 50 which each lead to a flexible pipe 59 connected to an oil-inlet fitting 8. At 60 is a valve for admitting oil from the pipe 55 to either pipe 56.

55 Steam or air is admitted to the steam or air inlet fittings 10 by a series of elements paralleling those by which oil is admitted to the fittings 8. The elements for conveying the steam or air are given the same reference numerals as have been used for the 60 elements for conveying oil except that prime marks have been added to the numerals designating elements conveying the steam or air.

65 When the furnace is in operation, one

burner is projecting into the furnace through the opening 11, the valves 60 and 60' being turned to admit oil and steam to that burner, while the other burner is held outside the furnace by the counterweight 61 attached to 70 its operating cable 43. When it is desired to reverse the flow of fuel and gases through the furnace and its regenerators, the handle 53 on the cable attached to the idle burner is raised, allowing its supporting 75 carriage 15 to travel down its track and pass its burner tube 7 into the furnace. The valves 60 and 60' are shifted to cut off the oil and steam from the first burner and direct them to the second burner. The first 80 burner is then withdrawn from the furnace by the attendant pulling down on the proper handle 53, whereupon the first burner becomes idle.

Heretofore it has been necessary for the 85 attendant at the central regulating stand at the rear of the furnace, when he wishes to reverse the furnace, to cut off the oil and steam, walk to one end of the furnace and pull out the burner just in use, walk to the 90 other end of the furnace and insert the burner therein and then walk back to the regulating stand before he can turn the oil and steam into the burner. By this practice much time is lost as it has to be repeated for 95 each reversal of the furnace which occurs many times a day. By my invention all the operations required for reversal may be accomplished at one central place.

I claim:

1. In a reversing furnace, a melting hearth, a combustion chamber at each end of the chamber, an oil burner at each end of the furnace, a traveling support for each burner for projecting it into its adjacent combustion chamber and retracting it therefrom, an operator's stand, means at the stand having operative connection with each support, whereby the operator may so project and retract each burner at will, and means for supplying fluid fuel to either burner at will.

2. In a reversing furnace, a melting hearth, a combustion chamber at each end of the chamber, an oil burner at each end of the furnace, a traveling support for each burner for projecting it into its adjacent combustion chamber and retracting it therefrom, an operator's stand, means at the stand having operative connection with each support, whereby the operator may so project and retract each burner at will, and means at the said stand for supplying fluid fuel to either burner at will.

3. In a reversing furnace, a melting 125 hearth, a combustion chamber at each end of the chamber, an oil burner at each end of the furnace, a carriage supporting each burner, a track on which each carriage may travel toward and away from the adjacent 130

- combustion chamber, an operator's stand, means at the stand whereby the operator may cause each carriage so to travel at will, and means at the stand for supplying fluid fuel to either burner at will. 4. In a reversing furnace, a melting hearth, a combustion chamber at each end of the chamber, an oil burner at each end of the furnace, a carriage supporting each burner, a track on which each carriage may travel toward and away from the adjacent combustion chamber, each track having its outer end higher than the end nearest the furnace, an operator's stand, means at the stand whereby the operator may cause each carriage to travel at will outwardly on the said track and to allow each carriage to travel by gravity toward the furnace, and means at the stand for supplying fluid fuel to either burner at will. 5. In a reversing furnace, a combustion chamber at each end thereof, a separate oil burner for each combustion chamber, a traveling support for each burner movable to project its burner into the adjacent combustion chamber and retract it therefrom, an operator's stand at one end of the furnace, a separate operating means attached to each burner support and leading to the said stand, and means below the furnace floor to contain the operating means extending from the vicinity of the burner support to that of the stand. 6. In a reversing furnace a track opposite the combustion chamber thereof and comprising a pair of spaced outwardly-extending parallel rods, a carriage having travel thereon and comprising a vertical plate at each side of the track, a peripherally grooved wheel supported by the plates and having travel between the bars and having its groove registering with both rods, and means for controlling at will the position of the carriage on the track, and an oil burner supported by the carriage and arranged to be projected into the combustion chamber and retracted therefrom by the alternate operations of the carriage. 7. In a reversing furnace, a track opposite the combustion chamber thereof and comprising a pair of spaced outwardly-extending parallel rods, a carriage having travel thereon and comprising a vertical plate at each side of the track, a peripherally grooved wheel supported by the plates and having travel between the bars and having its groove registering with both rods, means for controlling at will the position of the carriage on the track, an oil burner supported by the carriage and arranged to be projected into the combustion chamber and retracted therefrom by the alternate operations of the carriage, and means for adjusting the angular position in a vertical plane.

Signed at Pittsburgh, this 18th day of February, 1921.

HORACE E. SMYTHE.
